UNITED STATES PATENT OFFICE.

MARY E. WEST, OF BINGHAMTON, NEW YORK.

THREAD HOLDER AND CUTTER.

SPECIFICATION forming part of Letters Patent No. 402,498, dated April 30, 1889.

Application filed October 5, 1888. Serial No. 287,288. (No model.)

To all whom it may concern:

Be it known that I, MARY E. WEST, of Binghamton, county of Broome, in the State of New York, a citizen of the United States, have 5 invented certain new and useful Improvements in Thread Holders and Cutters, of which the following is a specification, reference being had to the accompanying drawings, in which—

10 Figure 1 is an end elevation. Fig. 2 is a side elevation. Fig. 3 is a side elevation showing the knife. Fig. 4 is a sectional view.

This invention relates to an attachment for 15 spools for the purpose of securing the loose end of the thread and cutting it at any length desired.

My object is to produce such an attachment cheap in construction and of great utility.

My invention consists in the several novel 20 features of construction and operation hereinafter described, and which are specifically set forth in the claim hereto annexed.

It is constructed as follows: A is the spool, to one end of which is secured an L-shaped 25 metal plate, B.

1 is a slotway or thread-channel, through which the thread passes from the spool.

2 is a piece of rubber or other like material secured to the plate B, with a slotway in its 30 upper face.

3 is the foot of the L-shaped plate, with its center and part of its side removed, and having its upper inner edge sharpened for the purpose of cutting the thread.

35 It is operated as follows: When thread is

drawn from the spool through the slotway 1 to the desired length, I draw it down into the slit in the rubber tube, which from its elastic nature grips the thread, and then passing the thread into the slotway and under the knife 40 a slight pull cuts off the thread, leaving the thread still gripped in the slit of the rubber block and held thereby in conjunction with the slotway 1 against unwinding. From this it will be observed that the function and purpose of the rubber block with its slit are to hold the thread both while it is being cut off and afterward against unwinding from the spool. When any desired length of thread is unwound, it is passed through the slotway 1, 45 thence through the slotway 4 in the rubber 2, and thence along under and through the removed portion of the foot 3, where it is severed, thus cutting the thread at any desired length and securing the loose end. 50

55 What I claim as my invention, and desire to secure by Letters Patent, is—

The combination, with a spool and a thread wound thereon, of a metallic plate secured to the spool and provided with a slit in its outer 60 end and a knife upon its inner end, and a slitted rubber secured between the knife and slit, substantially as described.

In witness whereof I have hereunto set my hand this 17th day of September, 1888.

MARY E. WEST.

In presence of—

H. P. DENISON,
C. W. SMITH.
